(57) **CLAIM**

The ornamental design for an electronic cigarette assembly, as shown and described.

DESCRIPTION

FIG. 1 is a front, top perspective view of an electronic cigarette assembly, shown in a fully assembled configuration, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded perspective view of the electronic cigarette assembly;

FIG. 10 is a front, top perspective view of the electronic cigarette assembly, with bottom portion removed for clarity of disclosure;

FIG. 11 is a rear, bottom perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof;

FIG. 18 is a front, top perspective view of the electronic cigarette assembly, with top portion removed for clarity of disclosure;

FIG. 19 is a rear, bottom perspective view thereof;

FIG. 20 is a front elevation view thereof;

FIG. 21 is a rear elevation view thereof;

FIG. 22 is a left side elevation view thereof;

FIG. 23 is a right side elevation view thereof;

FIG. 24 is a top plan view thereof; and,

FIG. 25 is a bottom plan view thereof.

(Continued)

The broken lines in the figures illustrate portions of the electronic cigarette assembly that form no part of the claimed design.
